UNITED STATES PATENT OFFICE

168,859

SHIRT

Everett S. Ruskay, Cedarhurst, N. Y., assignor to Publix Shirt Corporation, New York, N. Y., a corporation of New York

Application January 3, 1952, Serial No. 17,907

Term of patent 3½ years

(Cl. D3—25)

To all whom it may concern:

Be it known that I, Everett S. Ruskay, a citizen of the United States, residing in Cedarhurst, in the county of Nassau, State of New York, have invented a new, original, and ornamental Design for a Shirt, of which the following is a specification, reference being had to the accompanying drawing, forming a part thereof.

In the drawing:

I claim:

The ornamental design for a shirt, as shown.
EVERETT S. RUSKAY.
